(57) **CLAIM**

The ornamental design for an automobile wheel, as shown and described.

DESCRIPTION

FIG. 1 is a perspective view of an automobile wheel showing my new design;

FIG. 2 is a rear perspective view thereof;

FIG. 3 is a rear elevation view thereof;

FIG. 4 is a front elevation view thereof;

FIG. 5 is a side elevation view thereof, the top and bottom being the same in appearance; and,

FIG. 6 is a rear elevation view of a second embodiment of FIG. 1, the only difference being the lug aperture pattern, it being understood that all other surfaces are the same as those of the first embodiment.

The broken lines show the automobile wheel tire and form no part of the claimed design.
